York, N. Y., a corporation of Delaware

Application May 19, 1944, Serial No. 536,301

12 Claims. (Cl. 179—15)

1

This invention relates to pulse communication systems, especially multi-channel systems, incorporating relay and in and out branching stations.

In communication by means of pulses many methods of modulating the pulses to convey intelligence have been proposed, for example, various types of pulse time modulation (hereinafter abbreviated as "P. T. M.") have been proposed. Pulse amplitude modulation (hereinafter abbreviated as P. A. M.) has also been proposed.

In the co-pending application of Emile Labin and myself for "Multi-channel communicating systems," filed April 7, 1944, bearing Serial Number 529,933, now Patent No. 2,428,118, granted September 30, 1947, it has been suggested that the same pulses may be time modulated to convey intelligence and amplitude modulated to convey additional intelligence.

In order to satisfactorily communicate by P. A. M., it is essential that substantial deterioration of signal to noise ratio and distortion of the pulses be avoided. This requirement limits the use of P. A. M. to comparatively short distances or entails the use of relatively expensive linear relay stations. On the other hand, P. T. M. pulses may be substantially distorted and attenuated as regards amplitude and yet serve to adequately convey the intelligence represented by that type of modulation. Therefore P. T. M. may be used over much longer distances than P. A. M. without adverse effects. Moreover if the distances are so great as to require amplification of the P. T. M. pulses, then relatively inexpensive non-linear relay equipment may be employed.

It will, therefore, be seen that while P. T. M. is suitable for long distance transmission, P. A. M. is not, unless expensive linear relay stations are employed. This statement applies whether the communication is carried on by common line transmission, carrier wave line transmission, through a radio link, or otherwise. In using the term "short distance," I am using it in a special sense to refer to a distance which will not produce substantial distortion and attenuation of P. A. M. pulses, while a "long distance" will produce such distortion and attenuation. The actual physical distance implied by these terms depends upon the communication medium and other factors such as the frequency, power, and equipment employed.

An object of the present invention is the provision of a communication system which makes efficient use of the combination of P. A. M. and P. T. M. In one form this is accomplished by using P. T. M. for long distance transmission and

2

superimposing P. A. M. on the P. T. M. pulses to provide additional channels for communication over lesser intermediate distances, which lesser distances may be "short distances" in the special sense hereinabove defined, or may be greater than said short distances where the amount of traffic warrants the use of linear repeaters.

Another object of the present invention is the provision of a communication system including 10 two stations between which communication is held by P. T. M., said system including a relay station for said P. T. M. communication, which relay station is adapted to have additional communication with either another similar relay station or with one of said P. T. M. stations by means of P. A. M. carried on the P. T. M. pulses.

Another object of the present invention is the provision of a multi-channel pulse communication system in which communication is carried on between two main stations by P. T. M. pulses, and additional communication is carried on between 20 one or more intermediate relay and in and out branching stations and any other station by means of P. A. M. carried by the P. T. M. pulses.

Other and further objects of the present invention will become apparent and the foregoing will be best understood from the following description of embodiments thereof, reference being had to the drawings, in which:

30 Fig. 1 is a schematic diagram of a communication system embodying my invention;

Fig. 2 is a schematic and block diagram of a relay unit for use with a single channel of pulses in accordance with my invention;

35 Fig. 3 is a schematic and block diagram of a relay unit for use with multi-channel pulses; and

Fig. 4 is a set of curves to which reference is made in the following description. It is to be understood that these curves and others shown 40 in the drawings are not drawn to scale and only have significance to the extent pointed out herein.

In the embodiment illustrated in Fig. 1, communication is to be carried on between two stations which are designated as west station 1 and 45 east station 2. The communication medium may be by common line transmission, carrier wave line transmission or by means of radio links or any other suitable form of communication. In the embodiment shown in Fig. 1, the communication medium is illustrated, for example, as being common line transmission and consists of a line generally designated by the numeral 3 for traffic in an easterly direction and a line 4 for traffic in a westerly direction.

55 Assuming that west station 1 and east station

2 are a relatively long distance apart, in accordance with my invention communication between said stations is carried on by means of P. T. M. pulses such as those designated by the numeral 5.

Any suitable known type of P. T. M. modulator may be used, it being considered sufficient to point out that pulses 5 may be displaced in time within the limits indicated by the dotted lines 6.

The P. T. M. pulses transmitted from west station 1 which are modulated with intelligence at said station may be transmitted over long distances and if the distances are sufficiently long, non-linear repeaters 7 may be inserted in the sections 8 of the line covering said long distances. The fact that repeaters 7 are non-linear will not materially affect the communication by P. T. M. pulses. The pulses 5 arrive at a station 9 which, for purposes of conciseness, shall be termed "a relay station." At relay station 9, the P. T. M. pulses 5 are amplified and transmitted over a short distance line section 10 to another relay station 11.

It may be desired to carry on local communication between relay stations 9 and 11 and for this purpose the P. T. M. pulses which are relayed as station 9 may be pulse amplitude modulated by means such as described hereinafter to carry additional intelligence to station 11 as illustrated by pulses 12. At station 11 the pulses 12 are treated so as to remove the P. A. M. and derive the information represented thereby. The P. T. M. pulses are sent on towards east station 2.

It may be desired to carry on additional local communication between station 11 and station 2 and for this purpose the P. T. M. pulses transmitted from station 11 to station 2 may again be amplitude modulated with additional intelligence as represented by pulses 13.

If section 14 of the lines between station 11 and station 2 is greater than a "short distance," repeaters may be necessary. Since sections 14 are to carry P. A. M. as well as P. T. M., it will be necessary to use linear repeaters 15 for this purpose. At east station 2 the intelligence carried by the P. A. M. and the separate intelligence carried by the P. T. M. of pulses 13 may be derived from said pulses by any known forms of P. T. M. and P. A. M. demodulators.

In the pulses travelling from east station 2 to the west station 1 by line 4, local P. A. M. communication may be carried on in a similar manner between station 2 and station 11 as well as between station 11 and station 9. However, P. A. M. is not carried on between station 9 and west station 1 because of the length of the lines involved and the non-linear repeaters 7.

From the foregoing description it will be seen that communication is carried on by P. T. M. between the east station and west station while local communication is carried on between relay station 11 and either the east station or relay station 9 by P. A. M. carried by the P. T. M. pulses.

While I have described the foregoing communication system with reference to a single channel of P. T. M., it may also be used as a multi-channel system and the relay stations 9 and 11 may also serve as in and out branching stations not only for P. A. M. but also for P. T. M. Furthermore, although I have shown a given number of stations, it will be apparent that many more relay stations may be incorporated in the system in accordance with the foregoing description.

Referring now to Fig. 2, I have there illustrat-

ed a relay and in and out branching unit 16 for a single channel which unit may be employed in any one of the stations. This unit is designed to receive pulses 17 having both P. A. M. and

5 P. T. M. Pulses 17 are fed through a decoupling amplifier 18 and a low-pass filter 19 to an indicating device such as a receiver 20. In the low-pass filter 19, the pulses are integrated so as to yield a resultant wave 21 representing the intelligence with which pulses 17 were amplitude modulated. Pulses 17 are also sent through a limit clipper amplifier 22 where they are clipped along the level 23 and amplified and inverted to produce pulses 24. Pulses 24 still carry the intelligence represented by their time modulation but they have no amplitude modulation.

If unit 16 is also used as a P. T. M. "out" branching station then switch 25 is closed and pulses 24 are sent through a pulse time de-modulator 26 of any known type, such for example as disclosed in U. S. patent to Reeves No. 2,266,401, and a low-pass filter 27 to a reproducing device 28. The domodulator 26 serves to translate the time displacement of pulses into amplitude displacements. The low-pass filter 27 serves to eliminate any high frequency components.

If unit 16 is also used as a P. T. M. "in branching" station, then switch 29 is also closed and pulses 30, produced by a P. T. M. modulator 31 such for example as disclosed in the aforementioned Patent No. 2,266,401, and time-modulated by a signal from a source 32, are fed through the circuit including switch 29 to an amplitude-modulating circuit 33. The wave generator 34 for producing a control wave for modulator 31 may be synchronized by means of pulses 24 so that the pulses 30 will have the same timing as the pulses 17 in the absence of time modulation.

If unit 16 is not to be used as a P. T. M. "in branching" and "out branching" station then switch 35 is closed while switches 25 to 29 remain open. In this case pulses 24 are relayed. When switch 29 is closed and switch 35 open, then pulses 30 are transmitted.

Either pulses 24 or the pulses 30 are fed through an amplitude modulating circuit 33 having a tube 36 where the pulses are amplitude modulated with a signal 37 from a source 38 which may be a microphone or the like to thereby produce pulses 39 which carry both P. T. M. and P. A. M. The pulses 24 or 30 are fed to grid 40 of tube 36 while signal 37 is fed to screen grid 41 of tube 36. The pulses 24 and signal 37 combine to produce pulses 39 in the anode circuit 36.

The unit of Fig. 2 thus, not only amplifies and relays the P. T. M. pulses, but also removes P. A. M. from received pulses and adds by amplitude modulation further intelligence to the output pulses. The unit may also be used to demodulate the P. T. M. of the pulses, if desired, and to introduce a new series of P. T. M. pulses. Since the unit is intended to handle only one way traffic, two of such units may be employed in relay station 11 to handle two way traffic.

If the system illustrated in Fig. 1 is to be used for multi-channel P. T. M. communication, multi-channel units such as unit 43 illustrated in Fig. 3 and described in connection with the curves of Fig. 4 may be employed. One such unit suffices where one way traffic is handled and two of such units are used for two way traffic. Relay station 11 of Fig. 1, for example, if used for multi-channel communication, would include two such

units. Unit 43 is here described in relation to curves 44, 45, 46, 47, 48, 49, and 50 of Fig. 4.

Curve 44 represents a train of pulses in multi-channel communication which carry both P. T. M. and P. A. M. These pulses are delivered to the input of unit 43 directly from the line 51 (Fig. 3), if common line transmission is employed, or from a receiving unit consisting of a receiving antenna 52 and a linear R. F. amplifier and detector 53 if a radio link is employed as the communication means.

In the specific type of multi-channel pulse transmission illustrated in curve 44, each channel is represented by a train of pulses timed to interleave in sequence with pulses of other channels to form a single train of pulses. In curve 44 three channels 54, 55, and 56 are illustrated. The pulses of one of the channels preferably is modulated with an identifying characteristic distinct from the pulse characteristics of other channels for synchronizing the receivers to the transmission sequence of the channels. Channel 54 of Fig. 4 is the selected channel which has been modulated with a distinct identifying characteristic as indicated by its greater pulse width. This distinct width characteristic is used to provide synchronization for the separation of the various channels.

The pulses of curve 44 are fed through a limit clipper 57 where they are clipped at a level 57a (see curve 44) so that all the pulses are of constant amplitude when delivered by the limit clipper to the next stage which consists of the channel selector 58. The channel selector 58 is adapted to select pulses according to their width and is tuned to select pulses of the channel having the distinct width characteristic used for synchronization, to wit, channel 54. The channel selector 58 which selects pulses according to their width may be of any known type, and may be of the form disclosed in the co-pending application of E. Labin and applicant, Serial No. 487,072, filed May 15, 1943, issued U. S. Patent No. 2,440,278, August 6, 1947, although the discrimination between two given pulse widths may be accomplished by any one of several well known pulse width discriminators.

The output of the channel selector 58 may be represented by the train of pulses illustrated in curve 45 which is produced by the pulses of channel 54. The pulses of curve 45 are shown delayed for a slight interval in relation to the pulses of channel 54 to allow for any delay that might occur during the selection process. It will be understood, of course, that the selector may be of the type capable of selection without delaying the selected pulse energy. Any delay, however, is of no particular significance since delay devices are required, as will be described hereinafter which are used to properly time the selected pulse energy.

The pulses of curve 45 are used to separate the various channels but in order to do so, it is preferable that these pulses be shaped to greater width and greater amplitude. For this purpose, the pulses of curve 45 are sent through a shaper 59 which may be a multivibrator or any other known type of shaper which will produce the desired effects. The output of shaper 59 is represented by curve 46, and the pulses there represented will be hereinafter called "separating pulses."

The separating pulses (curve 46) are fed through a series of delay devices 60, 61, and 62, each of said devices serving to delay the separating pulses a further amount. The devices are preferably adjustable, it being understood that 75

there may be many more channels than there are in and out branching circuits so that the adjustable feature allows choice of channel. The output of each of said devices 60, 61, and 62, is fed to mixers 63, 64, and 65 respectively.

Mixer 63 serves to separate channel 55 as illustrated in curve 47. Delay device 60 delays the separating pulses of curve 46 so that the separating pulses are coincident with the pulses of channel 55. The separating pulses are of greater width than the pulses of any of the other channels and the delay device is adjusted so that not only are the separating pulses and the pulses of channel 55 coincident but, the separating pulses are wide enough to allow for any shift in time due to time modulation of the pulses of channel 55. If the pulses of channel 54, from which the separating pulses are derived, are time modulated, the separating pulses will have to be further widened to allow for this. Usually it is preferred that the pulses of channel 54 should not be time modulated.

The mixer 63 includes a tube 66 on whose grid 67 the incoming train of pulses shown in curve 44 is impressed. The tube 66 also has a second grid 68 on which the separating pulses from delay device 60 are likewise impressed. Thus the pulses of channel 55 are given a greater amplitude than the pulses of other channels. Tube 66 is biased to cut-off below the level 69 of curve 47 so that only pulses appearing above said level will produce an effect in the plate circuit 70 of tube 66. Thus only the pulses of channel 55 will appear in the output of mixer 63, as shown in curve 48.

Mixers 64 and 65 operate in a similar manner to separate channels 56 and 54 respectively so as to deliver at their outputs pulses depicted in curves 49 and 50 respectively.

The channels 55 and 56 which have been separated in the mixers 63 and 64 consist of a plurality of pulses which carry both P. A. M. and P. T. M. These channels as well as channel 54 may then be treated in a relay unit of the type described in Fig. 2. For this purpose relay units 45, 71, 72 and 73 are connected to the output of mixers 63, 64 and 65. Thus each or selected ones of the channels may be treated so as to remove the amplitude modulation and derive the intelligence represented thereby, amplify the P. T. M. 50 pulses, and add thereto further intelligence as P. A. M. In addition, the P. T. M. of selected channels may be removed and new channels of P. T. M. substituted in synchronism in their places. Where new P. T. M. channels are to be 55 substituted for other channels as indicated in Fig. 2, it is important that the timing of the substitute channel pulses before time modulation is the same as the unmodulated timing of the replaced channel pulses. This is accomplished 60 by synchronizing the wave generator 31 to the average timing of the pulses 24.

The output of units 71, 72, and 73 are delivered to a mixer 74 which serves to interleave the pulses of the various channels to produce a single train of interleaved pulses. The output of the mixer 74 is then delivered to the transmission means which may consist of a common line 75, or a linear R. F. translator 76 connected to a transmitting antenna 77.

70 While I have described all the essential elements for a complete relay and in and out branching station which provides for amplitude modulation communication as well as time modulation, it is to be understood that it is not necessary to use all of these elements in any given

station. For example, in relay station 9 for traffic moving from the west station towards the east station, it is unnecessary to have the de-coupling amplifier 18, low-pass filter 19 and indicating device 20 shown in Fig. 2 since the pulses transmitted by west station 1 carry no P. A. M. Again in relay station 9 for the unit which is used for traffic going in a westerly direction, it is unnecessary to have the amplitude modulating unit 33 of Fig. 2 since the pulses which are sent from relay station 9 to west station 1 are only to carry P. T. M. and no P. A. M.

It will therefore be seen that many changes can be made in the number of elements of each unit selected for each station. Numerous other changes such as in the particular type of element employed may be made without departing from the teaching of this invention. Accordingly while I have described the principles of my invention in connection with specific embodiments, it is to be clearly understood that this description is made only by way of example and not as a limitation on the scope of my invention as set forth in the objects and the accompanying claims.

I claim:

1. In a communication system including a plurality of stations, means for communicating intelligence between two of said stations by the use of discrete time modulated pulses, said means including a relay station for amplifying and relaying said time modulated pulses, and means at said relay station for communicating additional intelligence between said relay station and one of said stations by superimposed amplitude modulation of said time modulated pulses comprising a source of intelligence signals and means for amplitude modulating said pulses with said signals.

2. In a communication system including a pair of communicating stations, means including two relay stations spaced from said communicating stations for relaying intelligence between said communicating stations by the use of time modulated pulses, and means for communicating additional intelligence between said relay stations by superimposed amplitude modulation of said time modulated pulses.

3. In a communication system including a plurality of stations, means for communicating intelligence between two of said stations by the use of time modulated pulses, said means including a relay station for relaying said time modulated pulses, one of said two stations including means for amplitude modulating said time modulated pulses superimposed in accordance with additional intelligence, said relay station including means for removing and demodulating the amplitude modulation of said time modulated pulses to derive the additional intelligence represented thereby.

4. In a communication system a relay station adapted to receive pulses time modulated in accordance with intelligence and amplitude modulated in accordance with additional superimposed intelligence, means for removing the amplitude modulation of said pulses and deriving the additional intelligence represented in said amplitude modulation, means for amplitude modulating the time modulated pulses in accordance with other intelligence, and means for relaying the resulting doubly modulated pulses.

5. In a multi-channel pulse communication system, a relay station adapted to receive a plurality of pulses representing more than one chan-

nel, the pulses of at least one channel being time modulated with intelligence, means for separating the pulses of said one channel from the pulses of other channels, means for amplitude modulating the pulses of said one channel with additional superimposed intelligence, means for reinserting the pulses of said one channel among the pulses of the other channels, and means for relaying the pulses of the various channels.

6. In a multi-channel pulse communication system, a relay station adapted to receive a plurality of pulses representing more than one channel, the pulses of at least one channel being time modulated with intelligence and amplitude modulated with additional superimposed intelligence, means for separating the pulses of said one channel from the pulses of other channels, means for removing the amplitude modulation of the separated pulses, and means for reinserting the pulses representing said one channel among the other channels and relaying the pulses of the various channels.

7. In a multi-channel pulse communication system, a relay station as set forth in claim 6, including in addition means for amplitude modulating with other intelligence the separated pulses of said one channel before reinsertion of said pulses among the pulses of the other channels.

8. In a multi-channel pulse communication system, a relay station adapted to receive a plurality of pulses representing more than one channel, the pulses of at least one channel being time modulated with intelligence, means for separating said one channel for out branching purposes, means time controlled by the pulses of said out branching channel for generating pulses and time modulating said generated pulses in accordance with other intelligence, means to amplitude modulate said last-mentioned pulses in accordance with additional superimposed intelligence, means to reinsert said last-mentioned pulses amongst the pulses of other channels in place of the separated pulses, and means for relaying pulses of various channels.

9. In a multi-channel pulse communication system, a relay station adapted to receive a plurality of pulses representing more than one channel, the pulses of at least one channel being time modulated with intelligence and amplitude modulated with additional superimposed intelligence, means for separating the pulses of said one channel for out branching purposes, means time controlled by the pulses of said out branching channel for generating pulses and time modulating said pulses in accordance with intelligence, means for inserting said last-mentioned pulses among the pulses of other channels in place of the separated pulses, and means for relaying the pulses of various channels.

10. In a multi-channel pulse communication system, a relay station according to claim 9, including in addition means for also amplitude modulating the generated pulses in accordance with other intelligence superimposed before insertion of said pulses among the pulses of other channels.

11. In a multi-channel pulse communication system including a plurality of stations, means for communicating intelligence between two of said stations by multi-channel time modulated pulses, said means including two relay stations for relaying said multi-channel time modulated pulses, means for communicating additional intelligence between said relay stations, said last-mentioned means including means for separating

the pulses of one of said channels from the pulses of other of said channels, and means for superimposedly amplitude-modulating the pulses of the separated channel.

12. In a multi-channel communication system including a plurality of stations, means for communicating intelligence between two of said stations by the use of multi-channel time modulated pulses, said means including a relay station for relaying said time modulated pulses, and means for communicating additional intelligence between said relay station and another of the stations of the communication system, said last-mentioned means including means for separating the pulses of one of said channels from the pulses of other of said channels, and means for superimposedly amplitude-modulating the separated pulses.
